UNITED STATES PATENT OFFICE.

JAMES J. WADE, OF CHICAGO, ILLINOIS.

OVERFLOW AND WASTE FOR BATHS OR BASINS.

SPECIFICATION forming part of Letters Patent No. 556,388, dated March 17, 1896.

Application filed March 13, 1895. Serial No. 541,650. (No model.)

To all whom it may concern:

Be it known that I, JAMES J. WADE, a citizen of the United States, residing at Chicago, county of Cook, and State of Illinois, have 5 invented certain new and useful Improvements in Overflows and Wastes for Baths or Basins, which are fully set forth in the following specification, reference being had to the accompanying drawings, forming a part 10 thereof.

In the drawings, Figure 1 is a vertical section through a basin and the overflow and waste passages thereof containing my invention. Fig. 2 is a detail section containing the overflow 15 and waste passages in vertical plane, showing a modified form of my invention. Fig. 3 is a plan view of a modified form of the fitting shown in Fig. 2. Fig. 4 is an enlarged detail section of the lower end of the pillar 20 which receives the fitting in a plane at right angles to the plane of the section in Fig. 1. Fig. 5 is a side elevation of the handle or pull which operates the valve. Fig. 6 is a detail section of the fitting secured to the slab for 25 the guidance and support of the pull or handle, section being taken at the plane 6 6 on Fig. 1, looking upward.

The basin A has formed integrally with it in the earthenware a vertical passage A', 30 which extends directly through from top to bottom of the earthenware pillar a, located at the rear or side at which the water connections are located. It is designed that the slab B above the basin shall have an aperture B' 35 continuing the vertical passage, so that before the metallic fittings are applied there is a direct vertical passage at the top of the slab opening at the bottom of the earthenware. Through the wall of the basin the overflow- 40 apertures a' lead into this vertical passage A'. From the bottom of the bowl the ordinary waste-passage A² leads into the vertical passage A' at the side. C is a metallic fitting designed to afford a seat for a valve D, which 45 is adapted to close the communication from the direct waste-passage A² into the vertical passage A'. A suitable seat is not easily formed in the earthenware in this position, and one purpose of this invention is to retain 50 the advantages of the general arrangement shown and at the same time get a perfect seat for the valve, which is operated by a pull-knob

at the top of the slab, as will be hereinafter more particularly described.

The fitting C comprises the conical valve- 55 seat C' having a lateral opening C¹⁰, which, when the fitting is in place, registers with the mouth of the waste-duct A². The vertical passage A', which is cylindrical throughout, has a slight enlargement at the lower portion, 60 forming the small shoulder A¹⁰, and in this enlarged portion I form two longitudinal grooves a¹⁰ a¹⁰ at opposite sides, which lead from the lower end of the earthenware a short distance upward and there meet and merge 65 in interior circumferential grooves a¹¹ a¹¹, extending ninety degrees, more or less, around the vertical wall of the vertical passage.

The fitting C has two lugs C² C², projecting at opposite sides at the lower end of the 70 conical portion C' and adapted to enter the grooves a¹⁰ and a¹¹, and by this means the fitting is adapted to be inserted and locked in place by a short turn after the lugs c² reach the portion a¹¹ of the grooves. The lower 75 end, C³, of the fitting C is cylindrical and exteriorly threaded and of the interior diameter of the smaller end of the conical portion C', and is long enough to protrude below the fitting a sufficient distance to receive the cap 80 E, which is interiorly threaded and adapted to screw onto the exterior threaded portion, C³, of the fitting C, the flange of the cap embracing the circular boss which is formed by the lower end of the pillar a, through which the vertical 85 passage A' is formed. This fitting C is designed to be inserted from the bottom up against the shoulder A¹⁰, which is reached by the upper edge of the conical portion C' when the lugs C² are properly set in the grooves 90 a¹¹. The space that is left between the conical fitting and the cylindrical wall of the cavity into which it is thus entered the plumber will fill with "putty," and the cap E being screwed on the joint is complete without the 95 use of any washers or lead.

D is the valve, which is exteriorly conical and adapted to fit the conical seat C' and is hollow, so that when it is seated, closing the aperture C¹⁰, an unobstructed passage-way is 100 open through it from the overflow into the final waste-discharge. A connecting-rod, preferably of two or more parts loosely jointed together, connects the valve to the eye f in

the cross-bar f' of the cylindrical guide extension F' of the pull-knob F . To guide and seat this knob, a thimble G is provided, adapted to pass through the opening in the 5 slab and stopped by a suitable flange-shoulder G' at the top of the slab, the lower end of the thimble being threaded, so that it may receive a clamp-nut G^2 below the slab, whereby the slab may be bound tightly between the 10 flange-shoulder G' and said socket. The upper end of the pillar a has a recess or rabbet a^{12} , formed around the upper end of the passage A' , which accommodates the nut G^3 , so that it is not necessary to recess the slab for 15 this purpose. The thimble G has an interior bead or inwardly-projecting band G^3 around the upper margin of its aperture, said bead or band having the notches g^3 at opposite sides, and the cylindrical guide-flange F' of 20 the knob has a lug or tooth F^{10} , adapted to enter one of the notches, and at the upper portion it has two lugs F^{11} at opposite sides and ninety degrees from the tooth F^{10} , adapted simultaneously to enter the two 25 notches. The lower ends of the lugs F^{11} are above the upper level of the tooth F^{10} a distance a little greater than the width of the bead or band G^3 . This structure adapts the 30 knob to be inserted through the thimble, the tooth F^{10} passing down through either one of the notches until the lower ends of the lugs F^{11} rest upon the top of the thimble. In this 35 position the valve is off its seat, but entered into the fitting, so that it will be guided to its seat, if allowed to drop. The rotation of the knob ninety degrees admitting the lugs F^{11} to the notches, respectively, permits the 40 knob to drop until stopped by the interior projecting flange G^4 , which is formed around the lower margin of the fitting G of the thimble, and in this position the valve is fitted in the fitting C and the waste is closed, while the 45 overflow-passage is still open freely through the hollow valve.

Fig. 2 shows a modification of this device, in which the valve instead of being hollow is solid, the overflow-passage being formed alongside of it behind the valve-seat. In this case the valve-seat is formed in a frustum of 50 a cone which may be described within the cone frustum which constitutes the body of the fitting C , as is shown in the principal form, such described cone frustum merging at one side in the wall of the circumscribed frustum. 55 C^5 represents this described valve-seat. The seat proper, of course, is only the portion surrounding the aperture or mouth of the waste-passage A^2 ; but in order to cause the valve to come to this seat and be held against it the 60 cone frustum is completed in skeleton, com-

prising the upper segmental web, C^{50} , the lower segmental web, C^{51} , and a single oblique bar C^{52} connecting them in position preferably directly opposite the waste-opening. The jointed connection from the valve to the pull 65 device at the top of the pillar permits the valve, although not centrally located within the passage A' , to seat accurately by gravity, and to be easily pulled off its seat by the jointed connection, although the pull is not 70 exerted directly in line with the axis of the valve. When the valve is seated it will be understood that overflow passing out at the top of the bowl will escape behind the valve cage or seat described. 75

I have shown a special form of strainer II at the waste-outlet of the basin. This strainer has a short vertical annular flange II' , at the lower edge of which, at two opposite points, are provided horizontally-projecting lugs II^{10} 80 II^{10} . The earthenware has two notches h^{10} h^{10} at opposite sides of the circular opening formed to receive the strainer, and at the lower edge of the aperture I form rabbets II^{11} II^{11} extending ninety degrees from the notches 85 h^{10} h^{10} , respectively, so that when the strainer is introduced in place by passing the lugs II^{10} II^{10} down through the notches h^{10} h^{10} until the upper flange of the strainer seats in the rabbets h^{12} , formed for that purpose around the 90 upper margin of the opening, the lugs II^{10} II^{10} are in position to pass into the segmental rabbets h^{11} h^{11} as the strainer is rotated ninety degrees or less, and thereby the strainer is held 95 into place without cement, bolts or screws. 95

I claim—

In combination with the bath tub or basin having the pillar A apertured from top to bottom and communicating laterally with the waste-outlet and overflow-outlet, the metallic 100 seat-fitting adapted to be inserted in the lower end of the pillar and provided with a lateral aperture to register with the waste-outlet, said fitting being largest at the upper end, whereby a cavity is left around it accessible at the 105 lower end of the pillar after it is inserted adapted to receive putty or cement, and a cap-nut screwed onto the protruding end of said fitting to close the lower end of said cavity and bind the fitting to the pillar and receive 110 final waste connections: substantially as set forth.

In testimony whereof I hereunto set my hand, in the presence of two witnesses, at Chicago, Illinois, this 7th day of March, 1895.

JAMES J. WADE.
